REGENERATIVE REPEATER FOR
TELEGRAPH SIGNALS

Reginald Dennis Salmon, Croydon, England, assignor to Creed and Company Limited, Croydon, England

Application July 11, 1935, Serial No. 30,854
In Great Britain August 23, 1934

10 Claims. (Cl. 178—70)

This invention relates to regenerators for telegraph signals, and its object is to provide an arrangement whereby the percentage of each signal element used to determine its character is reduced to a minimum, and whereby the extreme accuracy required for this purpose may be achieved with the minimum amount of manufacturing care.

It is known in selector mechanism for type printing telegraph apparatus to cause an arm, released for rotation for each signal, to be moved axially in response to the successive elements of the signal and to cooperate with a series of selector members arranged in the circular path of movement of the arm.

This known mechanism was not intended as a regenerator. Its use for regenerating signals for re-transmission would be cumbersome, even if possible, and if the selector mechanism were to be used also as a regenerator, that is, accurately to pick out the middle of each signal element for that portion only to actuate the selector members, exceedingly accurate spacing of the selector members in the circular path of the rotating arm would be necessary and would be exceedingly difficult to ensure.

This invention uses the same principle of a rotating arm axially movable to actuate selectively a device arranged in its circular path of movement but by using this principle in a pure regenerator, leaving the selection to be performed separately by the regenerated elements of the signal, extreme accuracy can be secured much more easily, since the moment of regeneration is determined by a single point in the rotation of the arm.

According to one feature of the invention therefore a regenerator for telegraph signals comprises a rotatable member operable in axial direction by a magnet responsive to successive elements of received signals and released for a predetermined degree of rotation for each signal, the said arm cooperating with a single reproducing device adapted to be selectively actuated thereby in accordance with its axial position.

Preferably the single reproducing device comprises two members, one or other of which is struck by the rotatable member according to its axial position when passing the said members.

In one embodiment of the invention a striker pin is carried by a bell crank lever caused to execute a simple harmonic motion in one line by means of a cam. The striker pin passes through a slot in an extension of the armature lever of the receiving electromagnet and also through a

slot in a second bell crank lever. This slot is at right angles to the first slot and this second bell crank lever is also actuated by a cam to give to the striker pin a simple harmonic motion at right angles to the first said motion but 90° out of phase therewith. The resultant motion is a circular movement in a plane. The striker pin is also moved by the receiving magnet armature to and fro at right angles to this plane according to the character of the elements of the received signals.

It is arranged to be moved upwards in the gap between the ends of two latches at a moment corresponding to the middle of each signal element so that its position in the direction of the axis of its circular movement determines which of the two latches shall be struck. During the remainder of its circular movement the striker pin is entirely clear of the latches.

The two latches are carried by bell crank levers which normally rest against fixed stops and are held by springs thereagainst. The free ends of the bell crank levers tend to be pulled together by a spring, but the levers are prevented from moving by the fixed stops above-mentioned. These free ends also act on a double armed lever on a rock shaft which may carry contacts or operate a mechanical device. The movement of one of the latches by the striker pin raises its corresponding bell crank lever from the fixed stop and so allows that lever to move the rock shaft in one direction or the other depending on the particular latch actuated. The bell crank levers are reset immediately afterwards by means of a cam.

In the preferred embodiment of the invention a simpler device is used for giving circular movement to the striker pin or arm, and this embodiment will now be described with reference to the accompanying drawing which shows a perspective view of the regenerator as applied to regenerating the signals in a start stop telegraph system for the purpose of passing on the signals so regenerated to selector mechanism.

The armature 1 of the receiving magnet armature turns, in one direction or the other, a shaft 2 suitably mounted. This shaft carries two arms 3 and 4. Fixed to the arm 4 is one end of a shaft 5, the other end of which is carried by an arm 6 in such a manner as to be rotated thereby but to be freely movable in the direction of its length. The arm 6 is carried on a shaft 7 rotated as hereinafter described. The arm 3 when in the position shown holds a detent lever 8 in contact with a detent cam 10 on a shaft 12.

against a spring 9. The detent lever 8 is fixed to a rotatably mounted shaft 11 to which also is fixed a resetting lever 13. The shaft 12 carries a resetting cam 14 and a further cam 15. The 5 cam 15 acts on a detent lever, which is held by spring 17 against a detent cam 18 on shaft 7.

The shaft 7 also carries a pair of cams 19, 20 adapted to act upon the arms 21, 22 of a lever 23 pivoted on a pin 24. The lever 23 carries a 10 pin 25 on which levers 26 and 27 are pivoted. One end of each of these levers carries a pin 28 or 29 working in a slot 30 or 31 in the end of a link 32 or 33. The other ends of links 32 and 33 are fixed to opposite ends of an arm 34 carrying 15 a rod 35.

The lower ends of levers 26 and 27 abut against the ends of arms 36 and 37, pivoted on pins 38 and 39 and held against levers 26 and 27 and against fixed stops (not shown) by springs 40 20 and 41 respectively.

The shaft 5 carries an arm 42 normally opposite the ends of arm 37. The shafts 7 and 12 are driven through friction clutches from an electric motor but are normally held stationary by 25 the detents shown. The shaft 12 is arranged to execute one revolution in the time allotted to 6½ signal elements, the shaft 7 to make half a revolution in the time of one signal element.

The operation of the regenerator is as follows:—On the response of the magnet to the start signal the shaft 2 is rotated clockwise and the arm 3 moved away from detent lever 8. The latter is then withdrawn from the detent cam 10 by the spring 9 and the shaft 7 commences to 30 rotate. The movement of detent lever 8 brings arm 13 against cam 14 which serves in well known manner to restore the detent lever in 35 position to be retained by arm 3 during the stop period.

40 After the lapse of about 1¼ elements the end of the detent lever 16 comes on the high part of the cam 15 and is therefore raised against its spring 17 from contact with cam 18. Shaft 7 thereupon commences to rotate. Shaft 7 carries 45 round shaft 5 by means of arm 6 and thus arm 42 is rotated. The shaft 5 carrying arm 42 is moved axially according to the response of armature 1 to the elements of the received signal, so that arm 42 is positioned opposite arm 36 or arm 50 37 according to the nature of each element. Arm 42 therefore strikes one of these arms for each signal element and this is arranged to take place at the middle of the signal element. At the moment of striking or immediately thereafter the 55 arm 23, reciprocated by cams 19 and 20 is moved to the left in the drawing so that levers 26 and 27 are also moved to the left. The lower ends of these levers are brought against the ends of arms 36 and 37. Suppose arm 37 has been struck by 60 arm 42, it will have been moved into the position shown in the drawing, and the lower end of lever 27 will move over the end thereof. The lower end of lever 26 will strike against the end of the arm 36 that has not been moved. The lever 26 will 65 therefore pivot on pin 25 and its upper end will move to the left. By means of link 32 arm 34 and rod 35 carried thereby will be turned clockwise.

When arm 22 is moved back again it will carry 70 pin 25 and thus levers 26 and 27 but the pins 28 and 29 on these levers move in the slots in links 32 and 33 so as to leave arm 34 in the position into which it has been moved. Lever 27 is however carried clear of arm 37 which is restored by spring 41. Thus the striking of arm 36 or arm 75

37 by arm 42 according to its axial position turns arm 34 in one or the other direction.

After a period of five signal elements, that is 2½ revolutions of shaft 7, the end of arm 16 enters the hollow in cam 15 and spring 17 draws the 5 arm into position to engage with cam 18 whereupon shaft 7 is arrested.

The movements of arm 34 reproduce with greater force the movements of the armature 1 of the receiving magnet and are used to control 10 the selector mechanism of the teleprinter. In the case in which the regenerator is used with a receiving teleprinter it is only necessary to regenerate the five elements of the signal proper but the arm 34 or the rod 35 carried thereby could be 15 equipped with a contact tongue for retransmitting the signals. In that case the retransmission of the start and the stop signal would be controlled directly from shaft 12.

What is claimed is:

1. In a regenerator for telegraph signals, a magnet, a rotatable member operable in axial direction by said magnet responsive to successive elements of received signals and released for a predetermined degree of rotation for each signal, 25 a single reproducing device, means on said member repeatedly to cooperate during the regeneration of one telegraph code combination with said single reproducing device, and means on said reproducing device repeatedly selectively actuated 30 in the regeneration of one code combination in accordance with the successive axial positions of said rotatable member.

2. In a regenerator as claimed in claim 1 for a start-stop telegraph system, a shaft released for 35 rotation after the start signal for the period of five signal elements only, and a slidably mounting for said rotatable member in said shaft.

3. A regenerator as claimed in claim 1 in which the said reproducing device comprises two arms 40 one or other of which is adapted to be struck by the rotatable member according to its axial position.

4. In a regenerator for telegraph signals, a rotatable member, means for releasing said member 45 for rotation around its own axis for each code combination and for axially moving it in accordance with the character of successive elements of each signal, a pair of arms arranged in the respective paths of movement of said member, 50 and striker means for said member to strike one or the other of said arms repeatedly in the regeneration of one code combination.

5. A regenerator as claimed in claim 4 in which said striker means comprises a pair of levers, 55 means for periodically moving said levers to feel for the positions of the ends of said arms, a reproducing member linked to the arms, and means to move the reproducing member in one or the other direction according to the positions of said arms.

6. A regenerator as claimed in claim 4 and in which said striker means comprises a pair of levers, a third lever pivotally connected with said pair of levers, and cams on said rotatable member 65 cooperating with the ends of said arms.

7. A regenerator according to claim 1 and in which one axial position of said member corresponds to the marking and another axial position corresponds to the spacing element of the received signal, said means on the reproducing device being operated whenever said member is in the axial position corresponding to marking.

8. A regenerator for that type of telegraph signal in which each signal includes control pulses 75

for synchronizing purposes and marking or spacing intelligence pulses characteristic of the signal proper, which comprises an actuating member rotatable about its own axis, and axially displaceable along said same axis, means for rotating said actuating member through a predetermined angular distance in response to the reception of a control element of a signal, means for positioning said member in a first or second axial position in accordance with the marking or spacing nature of the characteristic elements of the received signal, a pair of actuatable members, one or the other of which is adapted to be actuated by said actuating member once for each characteristic element of a received signal.

9. A regenerator for signals of the type wherein a number of elements of varying character are included in each signal proper, comprising a single

device having a pair of actuatable members selectively operable into two different positions, a rotatable member, means for actuating said member through a predetermined degree of rotation about an axis in response to the reception of a signal, means for positioning said member in a given axial position in response to the reception of a signal element of given character, the said member being adapted when it is in said given axial position to strike one of said actuatable members of said device once for each element of the signal proper.

10. A regenerator as claimed in claim 9 for regenerating signals containing only five elements in each signal proper, wherein the said predetermined degree of rotation is more than one revolution.
